UNITED STATES PATENT OFFICE.

EARL W. PETERSON, OF CHICAGO, ILLINOIS, ASSIGNOR OF ONE-HALF TO NATIONAL STEEL DOOR CO., OF CHICAGO, ILLINOIS, A CORPORATION OF ILLINOIS.

METAL DOOR.

Application filed September 1, 1922. Serial No. 585,648.

To all whom it may concern:

Be it known that I, EARL W. PETERSON, a citizen of the United States, residing at Chicago, in the county of Cook and State of Illinois, have invented a certain new and useful Improvement in Metal Doors, of which the following is a specification.

- This invention relates to metal doors for use in fireproof buildings and the like, and 10 its object is to provide means by which the constituent parts of the door can be assembled with the minimum amount of work, consequent expense, and specifically with little or no punching, riveting or welding.
- 15 The invention consists in means attaining the foregoing objects; which can be very easily and cheaply made; which is satisfactory in use and is not readily liable to get out of order.
- 20 More particularly the invention consists in many features and details of construction which will be hereafter more fully set forth in the specification and claims.

Referring to the drawings in which like 25 numerals designate the same parts throughout the several views:

Figure 1 is a side view of the door illustrating this invention in its preferred form, a portion of the upper right-hand corner 30 being shown partially in section.

Figure 2 is a sectional plan view on the line 2—2 of Figure 1.

Figure 3 is a perspective view of certain 35 essential parts of the door construction showing the assembly method.

Figure 4 is an enlarged perspective view taken at the extreme upper end of Figure 3.

Figure 1 shows a conventional type of metal door having two parallel vertical stiles 40 10 and 12 connected together by any convenient number of cross-rails—in the particular case here illustrated three, 14, 16 and 18. The construction thus far described leaves spaces between the bordering stiles 45 and rails for two panels 20 and 22 which are identical except as to size. The finished door, shown, is rendered attractive in appearance by the presence of apparently merely decorative moldings 24 and 26 which 50 occupy the triangular spaces 28 and 30 formed at the junctures of the various panels with the bordering stiles or rails, as the case may be.

The problem solved by this invention is to 55 so construct the various parts referred to

that they may be assembled in the manner described practically without the use of rivets, solder, bolts or screws. In attaining the desired result, each rail or stile, as the case may be, is preferably made in box form 60 from a single sheet of metal, so folded that its edges in the final show-down form outwardly projecting parallel contacting flanges 30 and 32, making in effect a compound flange for the given stile or rail. Each of 65 these compound flanges 30—32 has punched through it at convenient intervals along its length perforations 34.

If it is desired that the finished door panels 20 and 22 shall be exactly in the middle 70 of the thickness of the door as determined by the thickness of the border member, stiles or rails, the border members are so constructed that these compound flanges 30—32 will be off-set to one side of the central axis of the 75 border member as clearly shown in Figure 2. The construction just referred to is not at all essential to the invention if for any reason the constructor is willing that the panel 80 shall not be central to the thickness of the door. In any event, these compound flanges 85 30—32 should be so placed that when the border member, stile or rail is placed around or adjacent to the panel, the panel and flange will occupy approximately the position shown in Figure 2 with just sufficient space between them so as to allow a plate member 24^a formed at an acute angle to the main portion of the molding 24 to lie between the flange and panel in such a position 90

that up-standing prongs or teeth 36 on the edge of plate member 24^a can enter the perforations 34, heretofore referred to, and perform the double function of positioning the flange members 30 and 32 with reference 95 to each other and preventing the movement of molding member 24 to the left, as viewed in Figures 2 and 3, away from the border member (10) of the door. The angularity of the member 24^a of the molding 24 is such 100 that when this molding is in place, it, as shown in Figure 2, engages both sides of the compound flange 30—32 and thus holds the flanges against separating movement one from the other. This molding 24, therefore, 105 in addition to closing triangular space 28 between the panel and border member, retains the border member itself in closed position without the use of bolts or rivets between the two flange members 30 and 32 110

and is itself retained in this covering position so that it cannot move over the panel member away from the border member. The parts thus far described are therefore self-locking, provided that means is provided for holding the panel member 20 against the member 24 of the molding 24. The mechanism for this purpose is of exceedingly simple construction and includes merely another molding member 38 on the side of panel 20 which is opposite the molding member 24, the same being, as before, of triangular form to close the space 30 between the panel and the border members, it being provided with a flat plate 38^a bearing against the panel 20 and a corrugated locking plate 40 adapted to spring under the corresponding corrugated latch plate 42, suitably secured to the adjacent border member, stile or rail by any suitable means as, for instance, the rivets 44. The result of the construction last described is that all the operator has to do to firmly lock the panel member against the plate 24^a of molding member 24 is to slip the member 40 of molding member 38 under corrugated latch member 42 which is of spring material until the locking device operates in obvious manner, whereupon the second molding member 38 is rigidly secured in place and all the other parts referred to are rigidly secured in place and the door has been so assembled without any hole punching except that for the perforations 34 and for the rivets 44. The operator has had to, in assembling, use no rivets, bolts, screws, solder or welding.

Having thus described my invention, what I claim as new and desire to secure by Letters Patent is:

40. 1. In mechanism of the class described, in combination with a panel and a bordering member, a flange projecting from the bordering member parallel to the side of the panel and adjacent to its edge, a molding on the same side of panel as and covering said flange, closing the angular space between the panel and bordering member, secured in place by means of a molding part which passes in between the panel and said flanges and enters a recess formed for it in said flange and means holding the panel against said molding and flange.
45. 2. In mechanism of the class described, a box-like border made from a sheet of flat material so folded that adjacent side edges project parallel to each other to form a double thickness flange in which there are formed transverse perforations, a panel projecting from the border member parallel to the flange, and a molding member covering said flange and the angular space between the border member and panel having a part which passes between the flange and panel and into the perforations in the flange to thereby secure the parts together, another molding opposite the first one adjacent to the border member and panel, and spring snap mechanism for securing the last mentioned molding in position to hold all the parts in place.
50. 6. In mechanism of the class described, a molding member having a flat portion for passage between a panel and a border member flange provided with projecting teeth to enter openings in such a flange and a covering portion at an acute angle thereto, adapted to cover the angular space between such a border member and such a panel.

and into the perforations in the flange to thereby secure the parts together.

3. In mechanism of the class described, a box-like border made from a sheet of flat material so folded that adjacent side edges project parallel to each other to form a double thickness flange in which there are formed transverse perforations, a panel projecting from the border member parallel to the flange, a molding member covering said flange and the angular space between the border member and panel having a part which passes between the flange and panel and into the perforations in the flange to thereby secure the parts together, and means holding the panel against said molding and flange.

4. In mechanism of the class described, in combination with a panel and a bordering member, a flange projecting from the bordering member parallel to the side of the panel and adjacent to its edge, a molding on the same side of panel as and covering said flange, closing the angular space between the panel and bordering member, secured in place by means of a molding part which passes in between the panel and said flanges and enters a recess formed for it in said flange, another molding opposite the first one adjacent to the border member and panel, and spring snap mechanism for securing the last mentioned molding in position to hold all the parts in place.

5. In mechanism of the class described, a box-like border made from a sheet of flat material so folded that adjacent side edges project parallel to each other to form a double thickness flange in which there are formed transverse perforations, a panel projecting from the border member parallel to the flange, a molding member covering said flange and the angular space between the border member and panel having a part which passes between the flange and panel and into the perforations in the flange to thereby secure the parts together, another molding opposite the first one adjacent to the border member and panel, and spring snap mechanism for securing the last mentioned molding in position to hold all the parts in place.

6. In mechanism of the class described, a molding member having a flat portion for passage between a panel and a border member flange provided with projecting teeth to enter openings in such a flange and a covering portion at an acute angle thereto, adapted to cover the angular space between such a border member and such a panel.

In witness whereof, I have hereunto subscribed my name.

EARL W. PETERSON.
